To all whom it may concern:

Be it known that I, WILLIAM TWEEDDALE, a citizen of the United States, residing at Brooklyn, in the county of Kings and State 5 of New York, have invented and produced a new and original Design for a Statue, of which the following is a specification.

The leading feature of this design consists 15 in a representation of a conical pile of stones, with a representation of an alligator upon the same with the front paws upon the upper part of the conical pile and the head in a nearly upright position.

The representation of the conical pile of stones is shown at A, the elevated head at B, the front paws at C, the hind paws at D, and the tail at E. This statue is usually employed 20 in connection with a fountain.

I claim—

The design for a statue herein shown and described, the same comprising a representation of an alligator upon a conical pile of 25 stones, substantially as set forth and represented.

Signed by me this 11th day of June, 1890.
